E. BOWEN.

PIPE WRENCH.

APPLICATION FILED SEPT. 29, 1919.

Patented Oct. 5, 1920.

UNITED STATES PATENT OFFICE.

EZRA BOWEN, OF BERKELEY, CALIFORNIA.

PIPE-WRENCH.

1,354,722.

Specification of Letters Patent.

Patented Oct. 5, 1920.

Application filed September 29, 1919. Serial No. 327,058.

To all whom it may concern:

Be it known that I, EZRA BOWEN, a citizen of the United States, residing at Berkeley, in the county of Alameda and State of California, have invented certain new and useful Improvements in Pipe-Wrenches, of which the following is a specification, reference being had to the accompanying drawings.

This invention relates to pipe wrenches, and the general object of the invention is to provide an extremely simple pipe wrench adapted to fit different sizes of pipe without the necessity of using relatively movable clamping jaws and attendant mechanism.

15 A further object is to provide a wrench which may be made so as to engage pipes of different standard sizes.

20 A further object is to provide a pipe wrench having a hook-shaped or curved terminal end provided with teeth, the shank of the wrench being so formed that when it is applied to a pipe of the proper size, the shank will force the pipe into engagement with the teeth, the teeth will bite into the 25 pipe and the wrench will bind upon the pipe upon a rotation of the wrench.

Other objects will appear in the course of the following description.

My invention is illustrated in the accompanying drawings, wherein:

30 Figure 1 is a side elevation of one form of wrench constructed in accordance with my invention;

Fig. 2 is a perspective view of the form of 35 wrench shown in Fig. 1;

Fig. 3 is a perspective view of a modified form of wrench.

Fig. 4 is a fragmentary elevation of another modified form; and,

40 Fig. 5 is a view in perspective of the bushing, as disclosed in Fig. 4.

In the drawings I have illustrated three different forms of my invention, the simplest of which is shown in Fig. 1. In this figure, it will be seen that the pipe wrench comprises a bar of steel formed to provide a shank 10, this shank at one end being laterally curved or bowed, as at 11, and then reversely curved, as at 12, so as to form a hook, the inner face 13 of which is directed toward the shank. The extremity of the bill of this hook is formed with teeth 14 and the shank immediately opposite the extremity has a relatively flat and longitudinally extending face 15.

When this wrench is applied to a pipe of

the proper size, the pipe is embraced between the teeth 14 and the face 15, as illustrated in Fig. 2, and then power is applied to the wrench in the direction of the arrow 60 in Fig. 2, which will cause the pipe to be wedged against the teeth and the teeth to bite into the pipe and thus the wrench and pipe will be caused to turn together. A reverse movement of the wrench will release 65 the pipe from its engagement therewith.

In Fig. 3 I illustrate a modified form of my invention, wherein the extremity of the hook 12 is provided with two sets of teeth 14 and 14^a, the teeth 14^a being adapted to 70 embrace another sized pipe from that acted upon by the teeth 14. Otherwise than this, the construction illustrated in Fig. 3 is exactly the same as that illustrated in Fig. 1. I do not wish to be limited to a pair of these 75 teeth 14 and 14^a, as still more teeth may be placed upon the end of the hook. Each of these sets of teeth is adapted to engage two sizes of pipe and thus it will be obvious that a wrench constructed in accordance with 80 Fig. 3, but having more than two sets of teeth, may be adapted to engage pipes having a large range in diameter.

In Fig. 4 I show still another form of my invention wherein the shank 10^a has the 85 same form as hereinbefore described, and is provided with the bill 12^a of the form previously illustrated, and having teeth 14^b.

B denotes a bushing adapted to be detachably engaged with the working face 90 of the shank of the bill 14, and each side margin of said bushing B is provided with a wing or flange 16 to overlay a side face of said shank, so that the bushing is effectively maintained in applied position. The bushing is longitudinally curved to closely conform to the curvature of the working face 95 of the bill 12^a, and this bushing B may be quickly applied when it is desired to employ the wrench in connection with pipes of different sizes.

In practice it is preferred that a wrench constructed in accordance with an embodiment of my invention be of soft steel, so that there will be no digging of the wrench 100 into the pipe or other work with which it is engaged.

From the foregoing description, it is thought to be obvious that a pipe wrench constructed in accordance with my invention is particularly well adapted for use by 110 reason of the convenience and facility with

which it may be assembled and operated and it will also be obvious that my invention is susceptible of some change and modification without departing from the principles and spirit thereof and for this reason I do not wish to be understood as limiting myself to the precise arrangement and formation of the several parts herein shown in carrying out my invention in practice except as hereinafter claimed.

10 I claim:—

1. A pipe wrench comprising a single shank bent at one end to form a hook, the extremity of the hook extending inwardly toward the shank and being formed with a toothed biting edge.
- 15 2. A pipe wrench comprising a single shank, rectangular in cross section, and bent outwardly in one direction at one end and then curved around and downward in the opposite direction to form a hook and reduced in thickness at the extremity of the hook, the extremity of the hook extending inward toward the shank and being formed
- 20 25 to provide a toothed biting edge, the teeth extending toward the inner face of the shank.
3. A pipe wrench comprising a single shank formed at its extremity with a hook, the extremity of the hook facing toward the

inner face of the shank, the extremity of said hook on the inner face thereof being formed to provide a plurality of series of cutting teeth each projecting from the inner face of the hook a different distance from 35 the teeth of any other series and facing toward the inner face of the hook.

4. A pipe wrench comprising a shank bent at one end to form a hook, the extremity of the hook extending inwardly toward the 40 shank and being formed with a biting edge, and a bushing adapted to be disposed upon the inner face of the shank opposite the hook and formed with means to embrace the shank and hold the bushing in place.

45 5. A pipe wrench comprising a shank bent at one end to form a hook, the extremity of the hook extending inwardly toward the shank and being formed with a biting edge, and a bushing adapted to be disposed 50 against the inner face of the shank opposite the hook, said bushing extending along the inner face of the shank and at its extremity abutting against the inner face of the hook-shaped portion and the bushing being provided with two ears embracing the shank.

55 In testimony whereof I hereunto affix my signature.

EZRA BOWEN.
